UNITED STATES PATENT OFFICE.

FRANK B. BRADLEY, OF CHICAGO, ILLINOIS.

GUARD-RAIL.

987,611.

Specification of Letters Patent. Patented Mar. 21, 1911.

Application filed December 24, 1910. Serial No. 599,149

To all whom it may concern:

Be it known that I, FRANK B. BRADLEY, a citizen of the United States, residing at Chicago, in the county of Cook and State 5 of Illinois, have invented certain new and useful Improvements in Guard-Rails, of which the following is a specification.

The object of my invention is to provide an improved guard rail to be used in accordance with the general practice in front of facing point switches, opposite frog points, and around curves for the purpose of guiding or deflecting wheel flanges to avoid derailment. The general, in fact almost universal, practice at present is to use 15 a piece of track rail of the same pattern as the running or traffic rails, and I am informed that there are less than one hundred guard rails in use in the United States that are not so constructed.

The particular features of novelty in my improved structure and the characteristic features of my invention will appear from the following description and claims, taken 25 in connection with the accompanying drawings in which—

Figure 1 is a plan view of my improved guard rail shown in connection with part of a traffic or running rail. Fig. 2 is an elevation of the structure shown in Fig. 1 looking from the inside of the track outwardly. Fig. 3 is an elevation view of the structure shown in Fig. 1 looking from the outside of the track inwardly. Fig. 4 is a cross section on the line 4 of Fig. 1. Fig. 5 is a cross section on the line 5 of Fig. 1 showing a supplemental brace which may be used if desired, but which is not necessary to the application of the broad features of my invention. Fig. 6 is a cross section on the line 6 of Fig. 1. Fig. 7 is a cross section on the line 7 of Fig. 1. Fig. 8 is a fragmentary sectional view on the line 8 of Fig. 2. Fig. 9 is a perspective view of the entire guard rail separate from the track rail. Fig. 10, is a detail perspective view of a separate brace which may be used with my improved guard rail, but which is not a necessary adjunct thereto. Figs. 11, 12 and 13 are views 45 of a modification, in which the base plate projects beyond the running rail continuously from end to end, as does also the flange upon the inner side of the guard rail, thus affording space for a continuous series

of spike holes to accommodate ties variously spaced.

In modern track construction the use of tie plates or surface plates between the ties and bases of the rails is becoming common by reason of the superior security afforded by such construction. It is quite customary, however, to omit the tie plates beneath frogs and beneath the guard and running rails opposite the frogs and it is not uncommon to construct track with tie plates on each tie and surface plates on each tie under the spring rail frogs, but with no metal bearing on the tie under the guard and running rail opposite the frog. The reason of this omission probably lies in the fact that the built-up forms of guard and running rail structures now in use, together with the separate chuck filling pieces, metal foot guards, guard rail clamps, etc., render the use of surface plates too expensive. It is my contention, however, that the surface plate under the guard and running rail, properly braced, is the best track practice and one of the objects of my invention is to provide a structure embodying this feature, the manufacture of which shall come within the limits of cost imposed upon such structures, and which shall be superior to built-up structures.

I have illustrated a form of guard rail adapted to lie along the track rail opposite a frog, but it will be understood that this particular form is selected for the purposes of explanation and that my invention is applicable to guard rails in the various connections in which they are customarily used.

Referring to Fig. 9, the guard rail proper is shown as consisting of an approximately vertical wall 1 rising from and integral with a base plate 2, which is designed to underlie the base 30 of the running rail 4, as clearly shown in the other views of the drawings. Also integral with the guard rail 1 is an inner support extending downwardly and inwardly from the guard rail or wall and provided with spike holes 5. This inner support forms a series of brackets between the ties and the guard rail or wall, and the brackets so formed may be merged in a continuous inner supporting wall as shown in Figs. 11, 12 and 13, or as shown in Fig. 1 may be discontinuous and spaced apart a distance equal to the spacing between the ties. The

base plate 2 in the form shown in Fig. 1 is provided with a series of extensions 6 opposite the brackets 3, which extensions project from the wall 1 a distance considerably greater than the width of the base or flange 30 of the running rail. Each of the extensions 6 is so formed that a spike may be driven through it in such position as to secure the running rail in place, provision being made to locate this spike in proper position to accommodate running rails having base flanges of different width. Provision is also made in each of the extensions 6 for the reception of a second spike in such relation to the extension as to restrain the guard rail structure against the inward thrust of passing wheels. In the particular form of my invention illustrated I effect this purpose by means of openings having an angular form—T-shaped as shown. The part of the opening 7 corresponding to the stem of the T lies transversely of the rail and is so positioned and of such size that the edge of running rails of all widths ordinarily used will lie over this part of the opening. This renders it possible, as illustrated in Fig. 6, to secure the running rail to the tie by means of a spike driven through the part 7 of the opening in the extension 6. The part 8 of the T-shaped opening lies parallel to the rail and a spike driven through this part of the opening will by its engagement with the outer wall thereof assist in restraining the guard rail structure against inward movement due to the thrust of passing wheels. It will be understood of course that the guard rail structure is further secured in place by spikes passing through the holes 5 in the brackets 3. The particular form of the spike opening in the extensions 6 of the base plate 2 may of course be varied, it being essential only that provision be made to receive one spike at varying points in order to secure running rails of different widths and that provision be made for another spike so located as to assist in restraining the guard rail structure against inward movement.

From the foregoing it will appear that I have embodied in a single integral structure a guard rail provided with means for spiking it to the ties upon its inner side and with an integral surface or base plate extending outwardly beneath the running rail and so formed as to admit of spiking the outer side of the running rails to the ties and for spiking the base plate itself to the ties on the outer side of the running rail. For the purpose of steadyng the running rail, I provide integral lugs 9 projecting outwardly from the wall 1 which constitutes the guard rail proper, these lugs being designed to lie above the inner base flange of the running rail. While I have shown in Fig. 7 a tight engagement between the base 30 of the running rail and the lug 9, it will be understood

that such tight engagement may not always be secured or be necessary in practice, or that, if desired, the lug 9 may be used in connection with wedges or other adjustable devices through which it may engage the base 30 of the running rail.

Owing to wear it frequently becomes necessary to adjust the position of a guard rail after it has been in use in order to restore the proper width of flange-way between the guard rail and the running rail. This object may be easily and expeditiously accomplished with my improved guard rail as above described. Referring to Fig. 6, and assuming that the wall 1 constituting the guard rail has become worn to such an extent as to widen the flange-way beyond the limitations of good practice, it is necessary only to withdraw the spikes, plug the spike holes with wooden plugs, replace the parts with the guard rail closer to the running rail and again spike the structure to the ties. The dimensions of the part 7 of the spike holes in the extensions 6 of the base plate 2 are such as to permit this adjustment within the necessary limits.

While not necessary to the application of the broad features of my invention, the separate braces 10, such as illustrated in Fig. 10 of the drawing, may be used upon the outer side of the running rail. When such separate braces 10 are used the extensions 6 of the base plate may be provided with upwardly extending shoulders 11 to take the thrust of the outer end of the braces 10 as clearly illustrated in Fig. 5. These braces may be formed with side notches 12 to receive spikes passing therethrough and through the opening in the base plate 2. When separate braces 10 are used they may be of the form illustrated or of any form or construction adapted to meet the varying adjustments of the running and guard rails.

Referring to Fig. 9, it will be seen that the base plate 2 extends throughout the length of the guard rail including the end portions thereof which flare from the running rail, and that when the structure is assembled with a running rail as shown in Fig. 1, the end parts of the base plate 2 underlie the running rail. In practice the ends of the guard rail where they flare or diverge from the running rail are continued longitudinally of the track a distance considerably beyond the point where the flanges of passing wheels ever contact therewith. By providing a base plate integral with the guard rail, as in my structure, and extending to the ends of the guard rail and underlying the running rail, the downward thrust of passing wheels is always transmitted directly to the guard rail structure before the flanges contact with the side of the guard rail. By this means the weight of a passing car or locomotive bears directly down

upon the guard rail and assists in holding it in place before any side thrust is imposed thereon by the flanges of the wheels.

In order to form a foot guard, I form the 5 ends of the guard rail 1 as illustrated.

Referring to Figs. 5, 6 and 7 it will be seen that the intermediate part of the guard rail presents an almost vertical wall opposite the running rail. This part of the guard 10 rail is parallel to the running rail. At about the point designated 15 upon Fig. 1 of the drawing, the guard rail diverges from the running rail and at these points the inner wall of the guard rail begins to assume an 15 inclined form sloping away from the running rail. This form may be conceived as resulting from the removal of the upper angle of the guard rail and increasing the amount removed as the end of the guard rail 20 is approached. As clearly shown in Fig. 4, at the point upon which that section is taken, namely—the line 4 of Fig. 1, the inner side of the guard rail slopes upwardly and outwardly from a point adjacent the base of the 25 running rail. The point at which this slope begins rises progressively toward the central part of the running rail, as indicated by the shaded angle designated 16 upon Fig. 9 of the drawing. This inclined surface 17, 30 which forms the foot guard, has an approximately triangular form with its base along the shaded line 18 at the end of the guard rail, as indicated in Fig. 1, and its sides consisting of the shaded angle 16 and the upper 35 edge 19 of the guard rail. By this means a foot guard integral with the guard rail is formed which serves the purpose of preventing the wedging of the foot of a passer-by between the guard and the track rail and 40 likewise prevents chains or other parts trailing from a car from becoming wedged at this point.

As shown in Fig. 7, I have shown the base plate 2 at the spaces between the ties as 45 extending under the running rail to a point approximately beneath the outer edge of the head thereof, and, as shown in the other views, I have provided the extensions 6 for the purpose of receiving spikes upon the 50 outer side of the running rail. Likewise I have shown the inner brackets 3 as spaced apart to lie over the ties. By this means an economy of metal is effected, but it will be obvious that the principle of my invention 55 is not limited to these precise forms, but may also be carried out as illustrated in Figs. 11, 12 and 13 which show a modified but equivalent structure. Between the ties I have reinforced the base plate 2 by means of trans- 60 verse ribs 20 designed to reinforce the base plate 2 in supporting the downward thrust on the running rail between the ties.

My improved structure as above described 65 may be formed of manganese steel, cast steel or malleable iron, or might be pressed from a

piece of plate steel, the application of my invention being independent of the particular material employed.

In Figs. 11, 12 and 13 I have illustrated a slightly modified form of my improved 70 guard rail. In this form the base plate 40 projects throughout its length beyond the traffic rail and the inner support 42 is also continuous. Rows of spike holes 43 and 44 are provided at the outer and inner edges 75 of the guard rail structure, the spike holes over the ties being used for the purpose of fastening the structure in place. This modification does not differ in principle from the form illustrated in Figs. 1 to 9, the parts 80 of the base plate 40 and of the inner supporting wall 42 over the ties constituting the extensions 6 and brackets or braces 3 of the form shown in those views. The modification shown in Figs. 11, 12 and 13 has some 85 advantage in its adaptability to ties differently spaced, but requires more metal in its manufacture.

While I have illustrated and described one specific embodiment of my invention for 90 the purpose of explaining the principle thereof, it will be understood that wide variations may be made in the specific mechanism without departing from the spirit of my invention.

I claim:

1. A guard rail structure comprising a guard rail, a base plate integral therewith and adapted to underlie the base of the traffic rail over and between the ties, and 100 brackets integral with said guard rail and adapted to be secured to the ties on the inner side thereof.

2. A traffic rail, a guard wall, a base plate integral with said guard wall, and of sufficient width to extend outwardly beyond the base of the traffic rail, ties, and means adjustable to different positions for securing the outer edge of the base of the traffic rail to the ties.

3. A traffic rail, a guard wall, a base plate integral with said guard wall, and of sufficient width to extend outwardly beyond the base of the traffic rail, ties, and means adjustable to different positions for securing the outer edge of the base of the traffic rail to the ties, and means for securing the inner edge of the base of the traffic rail.

4. A traffic rail, a guard wall, a base plate integral with said guard wall and projecting 120 outwardly beyond the base of the traffic rail, ties, means for securing the outer edge of the base of the traffic rail to the ties, the base plate being formed with an opening in which said means are adjustable.

5. A traffic rail, a guard wall, a base plate integral with said guard wall and projecting outwardly beyond the base of the traffic rail, ties, means for securing the outer edge of the base of the traffic rail to the ties, the 130

- base plate being formed with an opening in which said means are adjustable, and means for securing the inner edge of the base of the traffic rail.
- 5 6. A guard rail structure comprising a guard wall, a base plate integral therewith and adapted to underlie the base of a traffic rail over and between the ties, an inner support integral with the guard wall and extending downwardly and inwardly therefrom and adapted to be secured to the ties.
- 10 7. A guard rail structure comprising a guard wall, a base plate integral therewith, a traffic rail, ties, said base plate extending beneath the base of the traffic rail and terminating thereunder between the ties and having projections over the ties extending beyond the base of the traffic rail.
- 15 8. A guard rail formed integrally with a base plate adapted to underlie a traffic rail, and transverse strengthening ribs extending outwardly from said wall under said base plate.
- 20 9. In combination, a traffic rail, a guard rail, a base plate integral with said guard rail and underlying and extending outwardly beyond said traffic rail, said base plate having a spike hole therethrough of sufficient size transversely of the rail to receive a spike in different positions to secure the outer edge of the base of said traffic rail whereby said traffic rail may be secured by a spike passing through said base plate into the tie.
- 25 10. In combination, a traffic rail, a guard rail, a base plate integral with said guard rail and underlying and extending outwardly beneath the web of said traffic rail over and between the ties, said base plate having a spike hole therethrough adjacent the outer edge of the base of said traffic rail whereby said traffic rail may be secured by a spike passing through said base plate into the tie, and brackets integral with said guard rail and extending inwardly therefrom, said brackets being provided with spike holes.
- 30 11. A guard rail, a base plate integral with said guard rail and of sufficient width to underlie and extend outwardly beyond the base of a traffic rail, said base plate having a spike hole therethrough, said spike hole being of sufficient size to receive a spike in different positions whereby rails of different flange width may be secured to the tie by a spike passing through said spike hole.
- 35 12. A guard rail, a base plate integral with said guard rail and of sufficient width to underlie and extend outwardly beyond the base of a traffic rail, said base plate having a spike hole therethrough of sufficient size to receive a spike at varying distances from said guard rail on the outer side of a traffic rail.
- 40 13. A guard rail, a base plate integral with said guard rail and of sufficient width to underlie and extend outwardly beyond the base of a traffic rail, said base plate having a spike opening therethrough of sufficient size to receive a spike at varying distances from said guard rail on the outer side of a traffic rail, and also having a spike opening adapted to receive a spike at a pre-determined distance from said guard rail on the outer side of the traffic rail.
- 45 14. A guard rail, a base plate integral with said guard rail and of sufficient width to underlie and extend outwardly beyond the base of a traffic rail, said base plate having a spike opening therethrough of such size as to receive the traffic rail spike in proper position for rails having different flange width, and also having a spike opening the outer wall of which is designed to contact with a spike to restrain the guard against inward movement.
- 50 15. A guard rail, a base plate integral with said guard rail and of sufficient width to underlie and extend outwardly beyond the base of a traffic rail, said base plate having an opening to receive a spike in a selected position to secure the traffic rail, and being formed to receive a second spike in a position to secure the guard rail against transverse movement.
- 55 16. A guard rail, a base plate integral with said guard rail and of sufficient width to underlie and extend outwardly beyond the base of a traffic rail, said base plate having a spike hole of angular form, one part of said spike hole extending transversely of said rail and the other parallel thereto.
- 60 17. A guard rail, a base plate integral with said guard rail, and lugs projecting outwardly from said guard rail above said base plate and adapted to overlie the base of a traffic rail, said base plate having spike holes therein of sufficient size to receive at different points spikes engaging the outer edge of the base of a traffic rail.
- 65 18. A traffic rail, a guard rail structure comprising a guard wall, a base plate integral therewith and underlying and projecting outwardly beyond said traffic rail, shoulders on the outer part of said base plate, said shoulders being spaced from said traffic rail and adapted to support rail braces.
- 70 19. In combination, a traffic rail, a guard rail, a base plate integral with said guard rail and projecting outward beyond said traffic rail, shoulders upon the outer part of said base plate, braces engaging said shoulders and said traffic rail and spikes passing through openings in said braces and base plate.
- 75 20. In combination, a traffic rail, a guard rail, a base plate integral with said guard rail and projecting outward beyond said traffic rail, lugs projecting from said guard rail over the base of said traffic rail, shoul-

- ders upon the outer part of said base plate, braces engaging said shoulders and said traffic rail, and spikes passing through openings in said braces and base plate.
- 5 21. An integral guard rail structure comprising a guard wall and base plate adapted to underlie a traffic rail, said guard wall being formed to diverge inwardly at its ends from a traffic rail and also to diverge up-
10 wardly from the traffic rail throughout the extent of the inwardly diverging parts.
- 10 22. A traffic rail, a guard rail structure comprising a guard wall parallel throughout the length of its base to the inner flange of the traffic rail, and the top of said guard 15 wall diverging toward its ends from said traffic rail.
- In testimony whereof, I have subscribed my name.

FRANK B. BRADLEY.
